[57] CLAIM

The ornamental design for a perm rod holder, as shown and described.

DESCRIPTION

FIG. 1 is a perspective view of the perm rod holder showing my new design;

FIG. 2 is a side view thereof the side opposite appearing the same;

FIG. 3 is a front end view thereof;

FIG. 4 is a back end view thereof;

FIG. 5 is a top view thereof; and,

FIG. 6 is a bottom view thereof.

The broken line showing of the perm rod is for illustrative purposes only and forms no part of the claimed design.
